UNITED STATES PATENT OFFICE.

RALPH K. MAKER AND FRED S. MAKER, OF PROVIDENCE, RHODE ISLAND.

DESIGN FOR A COLLAR-HOLDER.

57,694.

Specification for Design.

Patented Apr. 26, 1921.

Application filed September 15, 1920. Serial No. 410,568. Term of patent 14 years.

To all whom it may concern:

Be it known that we, RALPH K. MAKER and FRED S. MAKER, citizens of the United States, residing at the city of Providence, county of Providence, State of Rhode Island, have invented a new, original, and ornamental Design for a Collar-Holder, of which the following is a specification, reference being had to accompanying drawing, forming part thereof.

Fig. 2 is a sectional side elevation of a collar holder showing our new design.

Fig. 3 is a top view of a collar holder showing our new design.

We claim:

The ornamental design for a collar holder, as shown.

RALPH K. MAKER.
FRED S. MAKER.
